DESULFURIZATION OF HYDROCARBONS WITH
A MIXTURE OF A GROUP VIII METAL AND
GROUP VIII METAL OXIDE OR SULFIDE

Archibald P. Stuart, Media, Pa., assignor to Sun Oil Company, Philadelphia, Pa., a corporation of New Jersey

11 Claims. (Cl. 208—244)

This invention relates to the separation of sulfur compounds from petroleum, and more particularly to the use of special adsorbent material in order to accomplish such separation.

It is often desirable to separate sulfur compounds from petroleum fractions in which they normally occur. Thus, mercaptans may be removed from light fractions such as gasoline to eliminate undesirable odor and improve lead susceptibility. In the case of fuel oil, it is often desirable to remove mercaptans and other sulfur compounds in order to meet specifications as to sulfur content. Sulfur compounds may be removed from charge stocks for catalytic reforming processes employing platinum-containing catalyst, in order to avoid undesirable effects of excessive amounts of sulfur on the catalyst.

In the case of lubricating oils, sulfur compounds can be separated therefrom in order to obtain sulfur concentrates which have valuable properties as anti-oxidants for various petroleum fractions. It would be desirable to obtain a greater extent of sulfur removal and greater concentration of sulfur in the removed material than are obtainable with prior art methods of obtaining such concentrates.

The process according to the present invention provides a highly effective manner of separating sulfur compounds from petroleum. The process is capable of being carried out at relatively low temperatures, for example in the approximate range from 50° F. to 300° F. The adsorbent material which is employed can be revivified for re-use by contact of the adsorbent with a desorbent liquid.

The process of the present invention involves, in one embodiment, first contacting petroleum material in liquid phase with a solid porous adsorbent intimately associated with a group VIII metal. It has been found that the presence of the group VIII metal promotes the selective adsorption of sulfur compounds. This permits a desulfurized hydrocarbon fraction to be obtained which has a low sulfur content and is obtained in good yield. It also permits a sulfur concentrate to be obtained which has only a relatively small amount of hydrocarbon material associated therewith.

Group VIII metals generally are suitable for use in preparing the desulfurizing agent. Nickel is a preferred metal for such use, but others such as cobalt, iron, platinum, palladium, rhodium, etc. can also be employed.

By use of a desorbent liquid, it is possible to first desorb the hydrocarbon materials from the adsorbent, and subsequently desorb sulfur compounds remaining on the adsorbent after the desorption of hydrocarbons. Usually, the amount of sulfur compounds desorbed will be within the approximate range from 80 to 100 percent of the sulfur compounds in the charge. If desired, the desorption of hydrocarbons can be performed in stages, obtaining first a fraction which is relatively concentrated with regard to saturated hydrocarbons (refractive index n_{D}^{20} about 1.46 to 1.50), then a mononuclear hydrocarbon concentrate (n_{D}^{20} about 1.50 to 1.54), then a dinuclear

aromatic hydrocarbon concentrate (n_{D}^{20} about 1.54 to 1.59), and so forth. In this type of operation, hydrocarbon fractions are obtained which, in addition to being desulfurized, are improved for subsequent use as a result of change in their hydrocarbon composition.

Thus, for example, a saturated hydrocarbon material obtained in the desorption generally has improved properties, in the case of a lubricating oil, with regard to viscosity index, or improved properties for use as a charge stock in a catalytic cracking as a result of removal of aromatic hydrocarbons therefrom. The aromatic hydrocarbon concentrate obtained in the desorption generally has improved properties for use as rubber processing oil or as oil to be employed in the manufacture of carbon black.

The adsorbent material which is employed as desulfurizing agent comprises in a preferred embodiment a porous adsorbent and a group VIII metal in intimate association. Any suitable manner of obtaining intimate association of the group VIII metal and the porous adsorbent can be employed in this embodiment. For example, the porous adsorbent in granular form can be impregnated with an aqueous solution of a salt containing the metal in question, e.g. nickel nitrate, a chloroplatinate salt, etc.; the impregnated adsorbent is then dried, calcined and reduced by contacting with hydrogen, thereby to obtain an adsorbent having the metal contained in the pores thereof. Another suitable manner of preparation involves forming a paste containing intimately admixed finely divided porous adsorbent and fine particles of the metal, and extruding the paste to obtain particles comprising the adsorbent and metal in intimate association.

In a preferred embodiment, the desulfurizing agent comprises a partially oxidized or partially sulfided group VIII metal. It is believed that partial oxidation or sulfidation forms metal oxide or metal sulfide at the most active sites of the metal, leaving the less active sites in the free metal state. The less active sites are sufficiently active to provide good adsorption of sulfur compounds, but not so active as to make it difficult or impossible to desorb the sulfur compounds. Thus, a more satisfactory adsorption-desorption operation is obtained than in the case where the metal is not partially oxidized or sulfided, and where sulfur compounds are too strongly adsorbed at the most active sites to be readily desorbed.

In this embodiment, the weight ratio of free metal to metal oxide or sulfide is preferably in the approximate range from 1:9 to 9:1, more preferably 1.2:1 to 2.4:1.

The partial oxidation or sulfidation can be performed in any suitable manner, preferably by contacting the metal with oxygen or a sulfur-containing material, e.g. hydrogen sulfide, under conditions to produce reaction of part of the metal to form the oxide or sulfide, part of the metal remaining in the uncombined state. Instead of proceeding from the uncombined state to the partially oxidized or sulfurized state, one can proceed from the combined state and convert part of the metal compound to the metallic state, e.g. by partial reduction of the metal oxide, part of the metal remaining in the combined state. Mixtures of metal and metal oxide or sulfur are known in the art as such, and in the light of the present specification a person skilled in the art can select suitable procedure for preparing such mixtures.

A particularly good desulfurizing adsorbent for use according to the invention is one comprising metallic nickel, nickel oxide or sulfide, and a porous adsorbent, the total nickel content of the desulfurizing agent being within the approximate range from 50 to 75 weight percent. 30 to 60 weight percent of the desulfurizing agent in this embodiment comprises metallic nickel, and 20 to 45 weight percent comprises nickel oxide or nickel sulfide or a mixture of nickel oxide and nickel sulfide,

It has been found that this desulfurizing agent provides particularly good selective adsorption of sulfur compounds.

The desulfurizing agent employed according to the invention preferably comprises a porous adsorbent in intimate association with the group VIII metal. However, it is also within the scope of the invention to use an agent, such as partially oxidized Raney nickel, which does not contain a separate porous adsorbent. Where a porous solid adsorbent is used, any such adsorbent can be employed. Such adsorbents are well known in the art as a class and include such materials as silica, gel, alumina, kieselguhr, bauxite, silica-alumina composites, fuller's earth, pumice, clays, etc. In this embodiment, the metal is preferably partially oxidized or sulfided, though the metal can be substantially entirely in the uncombined state.

The desulfurizing agent according to the invention can be prepared for example by impregnating silica gel particles with aqueous nickel nitrate solution, drying the impregnated gel at 260° F., calcining at 800° F. to convert nickel nitrate to nickel oxide, and partially reducing at 800° F. with hydrogen and steam. If desired, the nickel can be reduced substantially entirely to the metallic state and then re-oxidized to convert part of the nickel to the oxide. Another illustrative preparation of the desulfurizing agent involves impregnation of an adsorbent with ammonium chloroplatinate solution followed by slow drying and heat decomposition of the deposited salt. Any other suitable manner of preparation can be employed, which produces an intimate association of the adsorbent with a group VIII metal.

Any suitable desorbent liquid can be employed to remove hydrocarbons and sulfur compounds from the adsorbent. It is known in the art to perform various separations of mixtures of material by adsorption-desorption technique, wherein a porous solid adsorbent is first contacted with the material to be separated in liquid phase and then with a desorbent liquid to selectively remove certain of the materials adsorbed on the adsorbent. Materials which can be employed as desorbent liquids in such processing are well known in the art and include such compounds as n-pentane, benzene, ethanol, isopropanol, thiophene, etc. Any of the known desorbent liquids can be employed in the process according to the invention. Examples of suitable desorbent liquids are disclosed in United States Patent No. 2,585,490, issued February 12, 1952, to J. L. Olsen. A plurality of desorbent liquids having increasing polarity can be employed in series if desired to remove successively the more strongly adsorbed components of the charge stocks.

In one embodiment, the charge oil, prior to contacting with the desulfurizing agent according to the invention, is given a pretreatment in order to remove therefrom the most strongly adsorbable sulfur compounds therein. These compounds may constitute for example about 1 to 15 percent of the total sulfur compounds in the charge. If these sulfur compounds are not previously removed, they may remain on the desulfurizing agent in the subsequent step since they are sometimes difficult to remove by ordinary desorption technique. By removing them in a pretreatment, it is possible to obtain operation in which substantially all of the sulfur compounds can be desorbed from the desulfurizing agent, and the latter re-used many times. Any suitable manner of removing the most strongly adsorbable sulfur compounds can be employed in the pretreating step. Thus, for example, the pretreatment can involve contacting the charge oil with a separate portion of the same adsorbent which is employed in the subsequent step or with some other adsorbent such as clay. Treatment with concentrated sulfuric acid can also be employed to remove the most strongly adsorbable sulfur compounds. The desirability of the pretreatment will

depend on the nature of the charge, and in some instances at least pretreatment will not be necessary.

The process of the invention can be applied to petroleum fractions generally such as gasoline, naphtha, kerosene, fuel oil, lubricating oil, etc. Straight run or cracked fractions can be treated.

If desired, the contacting according to the invention can be performed in such manner that selective adsorption of sulfur compounds on the adsorbent is obtained, the hydrocarbon product being obtained as effluent from the adsorbent bed in the initial contacting, and the sulfur compounds remaining on the adsorbent being subsequently desorbed to obtain a single desorbed fraction. Preferably, however, the process is performed in such manner that a plurality of desorbed fractions are obtained, including a desulfurized hydrocarbon fraction or fractions and subsequently a sulfur concentrate or concentrates.

The following example illustrates the invention:

The charge oil was a lubricating oil distillate derived from naphthenic base crude and having the following typical properties: specific gravity d_4^{20} of 0.9340, refractive index n_D^{20} of 1.5153, Saybolt Universal viscosity at 100° F. of 603 seconds and at 210° F. of 55 seconds, and sulfur content of 0.26 weight percent.

The desulfurizing agent was a mixture of nickel and nickel oxide in intimate association with kieselguhr and had the following composition: nickel 43.6%, nickel oxide 28.2%, silica 19.9%, alumina 3.0% and graphite 4.0%. One-eighth inch pellets were crushed to a powder in a nitrogen atmosphere. 500 grams of the powder were placed in a column to provide a 4 foot packed section.

A solution of 25 grams of the charge oil in 50 ml. of n-pentane was introduced into the bed of desulfurizing agent. The following desorbents were used in series: 1450 ml. of 4% benzene in pentane, 1050 ml. of 10% benzene in pentane, 900 ml. of 24% benzene in pentane and 2000 ml. of 7% isopropanol in benzene. Effluent cuts were taken, desorbent stripped therefrom and the cuts composited into the fractions shown in the following table. Fraction 1 contained the first 10.6% of effluent oil, Fraction 2 the next 19.9%, and so forth. The sulfur content of each composite fraction is shown, also the cumulative weight percent of sulfur, based on total charge oil, contained in the effluent oil. Thus, Fraction 2 contained about 0.002% sulfur based on total charge, Fraction 3 about 0.003%, and so forth.

Fraction	Desorbent	Cumulative, Wt. Percent Oil	Wt. Percent Sulfur	Cumulative, Wt. Percent Sulfur
				50
55	4% benzene in n-pentane	10.6	0	
1	do	30.5	0.01	0.002
2	do	47.0	0.02	0.005
3	do	54.3	0.03	0.007
4	do	61.5	0.04	0.010
5	do	66.5	0.08	0.014
6	do	76.6	0.11	0.025
7	do	84.8	0.3	0.050
8	10% benzene in n-pentane	90.4	0.57	0.082
9	do	94.5	1.05	0.125
10	do	98.0	1.86	0.208
11	24% benzene in n-pentane	99.0	1.86	0.227
12	7% isopropanol in benzene			

These results show that the first 90 percent of effluent contained about 0.082/0.26, or about 31.6 percent of the sulfur in the charge stock, representing about 68.4 percent desulfurization of 90 percent of the oil. In other words, up to about 75 percent desulfurization of 90 percent of the charge was obtained. The total recovery of sulfur in desorbed fractions was about 0.277/0.26, or about 87 percent.

By way of contrast, only about 37 percent of the sulfur in the charge could be recovered in desorbed fractions from Raney nickel using desorption technique es-

sentially the same as that employed with the nickel-nickel oxide-kieselguhr adsorbent.

In the desorption of oil from the nickel-nickel oxide-kieselguhr adsorbent, the refractive index of the effluent oil increased steadily from about 1.48 for the first desorbed fraction to about 1.51 for Fraction 5 and to 1.6 at about Fraction 9, then decreased to about 1.58 at about Fraction 11, and rose again to about 1.59 at about Fraction 12.

In the preceding example, a plurality of desorbents having increasing polarity were employed in order to obtain a large number of desorbed fractions having gradually changing properties. It is to be understood that the entire desorption can if desired be performed with a single desorbing agent having constant composition, or with two desorbing agents in series, the latter having greater polarity, etc.

Thus, for example, 1000 ml. of 24% benzene in pentane is used in one embodiment as the sole desorbent, and a separation of sulfur compounds from hydrocarbons comparable to that disclosed previously is obtained. The sulfur compounds are in one embodiment desorbed in later portions of the same desorbent. In another embodiment, they are desorbed primarily with another desorbent having greater polarity, e.g. benzene, alcohol, mixtures of benzene and alcohol, etc.

Generally similar results, with regard to efficiency of sulfur separation, to those obtained in the above example, are obtained when treating other petroleum fractions such as gasoline, fuel oil, etc. Other group VIII metals can be employed in place of nickel.

The adsorption stage is preferably performed at relatively low temperature, e.g. 50° F. to 150° F., though higher temperatures, e.g. up to 300° F. or higher, can be employed if desired. The desorption stage can also be performed at relatively low temperature, e.g. 50° F. to 150° F., though higher temperatures, e.g. up to 300° F. or higher, favor desorption efficiency.

The process according to the invention provides in various embodiments new and improved manners of desulfurizing petroleum, reactivating the desulfurizing agent for re-use, recovering sulfur concentrates from petroleum, and separating petroleum into fractions having different hydrocarbon composition. The sulfur concentrates obtained from various types of petroleum charge stocks in certain embodiments can be employed for any of the known uses of such concentrates.

The invention claimed is:

1. Process for removing sulfur compounds from petroleum hydrocarbons which comprises: contacting petroleum hydrocarbons in liquid phase at a temperature within the approximate range from 50° F. to 300° F. with a desulfurizing agent comprising a group VIII metal

and a compound selected from the group consisting of an oxide and a sulfide of a group VIII metal, and contacting said agent with a desorbent liquid, thereby to desorb sulfur compounds.

5 2. Process for removing sulfur compounds from petroleum hydrocarbons which comprises: contacting petroleum hydrocarbons in liquid phase at a temperature within the approximate range from 50° F. to 300° F. with a desulfurizing agent comprising about 30 to 60 weight percent of metallic nickel and about 20 to 45 weight percent of a compound selected from the group consisting of nickel oxide and nickel sulfide.

10 3. Process for removing sulfur compounds from petroleum hydrocarbons which comprises: contacting petroleum hydrocarbons containing sulfur compounds in liquid phase with a porous adsorbent in intimate association with a group VIII metal, thereby to adsorb sulfur compounds; and contacting said adsorbent with a desorbent liquid, thereby to desorb sulfur compounds.

15 4. Process according to claim 3 wherein said adsorbent containing adsorbed hydrocarbons and sulfur compounds is first contacted with a desorbent liquid to selectively desorb hydrocarbons and recover a first effluent containing hydrocarbons having reduced sulfur content, and is then contacted with a desorbent liquid to desorb a sulfur compound concentrate.

20 5. Process according to claim 1 wherein said petroleum hydrocarbons constitute a lubricating oil fraction.

6. Process according to claim 3 wherein said petroleum hydrocarbons constitute a lubricating oil fraction.

25 7. Process according to claim 1 wherein said agent is prepared by partially oxidizing said metal.

8. Process according to claim 1 wherein said agent is prepared by partially sulfiding said metal.

30 9. Process according to claim 1 wherein said temperature is within the approximate range from 50° F. to 150° F.

10. Process according to claim 2 wherein said agent consists essentially of metallic nickel and nickel oxide.

35 11. Process according to claim 2 wherein said agent constitutes substantially the sole contacting agent.
